INTERFERENCE DIVERTER

Ralph F. Schuster, Albuquerque, N. Mex.

Application February 17, 1931. Serial No. 516,440

7 Claims. (Cl. 250—20)

The invention relates to a novel means for clarifying radio reception, and while the embodiments herein illustrated are all attachments for use with conventional receiving sets, the 5 invention may well be built into such sets at the factory.

The invention aims to overcome interference caused by discharges from local electrical appliances and it serves to collect the interfering waves and divert them to the ground so that 10 they cannot interfere with clear reception.

In the accompanying drawings, three forms of construction have been illustrated and will be rather specifically described, with the understanding however that within the scope of the invention as claimed, numerous variations may be made.

Fig. 1 is a longitudinal sectional view on line 1—1 of Fig. 2.

Fig. 2 is a longitudinal sectional view at right angles to Fig. 1, as indicated by line 2—2 of the latter.

Fig. 3 is a transverse sectional view on line 3—3 of Fig. 1.

Figs. 4 and 5 are perspective views showing the two sections of the insulating block which may be conveniently used as housing means for the parts of the invention hereinafter described.

Fig. 6 is a view similar to Fig. 1 but showing 20 a different form of construction.

Figs. 7, 8 and 9 are sectional views on the correspondingly numbered lines of Fig. 6.

Fig. 10 is a view similar to Figs. 1 and 6 but showing a still further form of construction.

Figs. 11 and 12 are sectional views on lines 25 11—11 and 12—12 of Fig. 10.

In the form of construction shown in Figs. 1 to 5, a one-piece elongated conducting core

40 15 of copper or other appropriate material, is employed, said core being provided with a binding post 16 or with other equivalent connecting means for a ground wire 17. Near one of its ends, the core 15 is provided with a circumferentially extending flange 18 in conductive connection with said core. Near the other end of the core, the latter is surrounded by a conducting ring 19 which is insulated from said core as denoted at 20. A plurality of conductors 21 extend between the flange 18 and the ring 19, are spaced apart about the core, and are soldered or otherwise secured to said flange and ring, said conductors 21 being formed of copper wire or of strands or strips of any other preferred material.

50 These conductors 21 are of course in conductive connection with the flange 18.

An elongated coil 22 of copper or other preferred conducting material, surrounds the core 15 within the confines of the conductors 21, said coil being out of conductive connection with all of the aforesaid parts. The ends of coil 22 are 60 connected with binding posts 23 and 24 to which wires 25 and 26 may be connected, one wire leading from the aerial and the other to the set so that the coil 22 forms part of the lead-in wiring of the set.

The parts above described may be conveniently carried by an insulating block formed of two sections 27 and 28 which are recessed at 29 to jointly form a cavity 30 receiving the major portion of the core 15, the coil 22, the 70 conductors 21 and the elements 18, 19 and 20. The block sections 27 and 28 may well be provided with notches 31 receiving the ends of the core 15, and one end of said core may be secured within one notch 31, by means of the binding 75 post 16. As shown, the block section 27 is additionally notched or grooved at 32 to receive the ends of the coil 22, said section 27 carrying the binding posts 23 and 24 as well as the binding post 16. Bolts or the like 33 may be employed for securing the two block sections 27 and 28 together.

By means of the binding posts 23 and 24, the device is connected in any desired portion of the lead-in wiring of a radio-receiving set, and the 85 binding post or other connection 16 is connected with the wire or the like 17 leading to the ground. The radio waves and the interfering waves travel along the coil 22, and said interfering waves are collected by the conductors 21 90 and the core 15 and diverted to the ground, whereas the radio waves pass on to the set, giving clear reception.

In the form of construction illustrated in Figs. 6 to 9, the sections 27^a and 28^a of the sectional block, are recessed in ways above described and are additionally provided with lateral notches 34 communicating with the cavity 30^a. The notches 34 receive and hold the ends of insulators 35 which span the cavity 30^a transversely. These insulators are preferably disposed in parallel planes and they are provided with disk-like central portions 36 and 37 respectively. Extending between the centers of these disk-like portions 36 and 37, is a composite core 15^a of 100 conducting material or materials.

One end portion of the core 15^a is formed from a plurality of thin plates 38 of copper or other appropriate material, said plates being disposed in planes which radiate from a central 110

line. At one end, the plates 38 are all anchored to the insulator portion 37, as indicated at 39. Conducting wires 40 are soldered or otherwise connected with the plates 38, are brought together at the free ends of said plates as indicated at 41, and are jointly extended to a binding post 16^a corresponding to the post 16, these wires forming a conductor 42. Two coils 43 and 44 of copper or the like surround the conductor 42 and are spaced apart along the same. These coils 43 and 44 are insulated substantially throughout their lengths from the conductor 42, the insulators being shown at 45. One end of each coil however is in conductive connection with the conductor 42, in any preferred way. For illustrative purposes, the ends 46 and 47 of the coils 43 and 44 respectively, may be considered as soldered to said conductor 42. The coil 43 is preferably formed from a plurality of strands of copper wire or the like, while the coil 44 may be of single strand form, also of copper or other preferred conducting material.

Two transversely curved, elongated strips 48 of copper or the like, extend between the insulator portions 36 and 37 and are suitably secured against the peripheral edges thereof, said strips being turned inwardly at one end and secured in a conductive manner to the conductor 42. The other ends of the strips 48 may well be secured to a ring 50 and it is preferred that an insulating disk 51 be interposed between this ring and the anchorages 39 of the plates 38.

Around the composite core above described, within the confines of the strips 48, is a coil 22^a corresponding to the coil 22 and connected at its ends with binding posts 23^a and 24^a respectively. The coil 22^a is shown of two-strand form, but this is not essential.

The composite core within and out of conductive connection with the coil 22^a, and the strips 48 around and out of conductive connection with said coil 22^a, collect the interfering waves and divert them to the ground.

In Figs. 10, 11 and 12, a further variation of construction, is illustrated. A single conductor 15^b is provided at one end with a flange 18^a corresponding with the flange 18. At its other end, the conductor 15^b is provided with radial plates 38^a corresponding with the plates 38, these plates 38^a being directly carried by and in conductive connection with said conductor 15^b. The parts 15^b, 18^a and 38^a form portions of the conducting core, the remainder of said core being constituted by coils 43^a and 44^a which correspond to the coils 43 and 44 above described. Transversely curved strips 48^a similar to the strips 48, engage the periphery of the flange 18^a and at one end are turned inwardly and secured at 49^a to the conductor 15^b. The other end of the strips 48^a are spaced by and secured to an insulating disk 37^a mounted on the conductor 15^b. Within the confines of the strips 48^a, is a coil 22^b corresponding to the coils 22 and 22^a. The ends of this coil are connected with binding posts 23^b and 24^b and said coil is out of conductive connection with all parts except these binding posts. The conductor 15^b is connected with the ground binding post 16^b.

The parts above described are carried by recessed block sections 27^b and 28^b. One end of the conductor 15^b is held by the binding post 16^b. The other end of this conductor is preferably provided with a head 52 held within notches or the like 53 in the block sections.

As in the forms of construction previously de-

scribed, the device shown in Figs. 10 to 12 acts to collect the interfering waves and divert them to the ground.

Extended experiments have proven that local interference caused by discharge from electrical appliances, is eliminated by the use of the device.

While excellent results may be obtained from any of the forms of construction herein illustrated, attention is again invited to the fact that within the scope of the invention as claimed, numerous variations may be made.

I claim:—

1. An interference diverter comprising a core of conducting material, a ground wire conductively connected with said core, an unbroken conducting coil surrounding said core and free of conductive connection therewith, a lead-in wire from an aerial conductively connected with one end of said coil, a lead-in wire for a receiving set conductively connected with the other end of said coil, said coil and said lead-in wires constituting an uninterrupted lead-in line from aerial to set, and a shell of conducting material around and out of conductive connection with said coil, said shell being in conductive connection with said ground wire. 90

2. An interference diverter comprising a core of conducting material, a ground wire conductively connected with said core, an unbroken conducting coil surrounding said core and free of conductive connection therewith, a lead-in wire from an aerial conductively connected with one end of said coil, a lead-in wire for a receiving set conductively connected with the other end of said coil, said coil and said lead-in wires 100 constituting an uninterrupted lead-in line from aerial to set, and a shell of conducting material around and out of conductive connection with said coil, said shell being in conductive connection with said ground wire. 105

3. An interference diverter comprising a core of conducting material, a ground wire conductively connected with said core, an unbroken conducting coil surrounding said core and free of conductive connection therewith, a lead-in wire from an aerial conductively connected with one end of said coil, a lead-in wire for a receiving set conductively connected with the other end of said coil, said coil and said lead-in wires 110 constituting an uninterrupted lead-in line from aerial to set, and a shell of conducting material around and out of conductive connection with said coil, said shell being in conductive connection with said ground wire. 115

3. An interference diverter comprising an elongated one-piece core of conducting material having a ground wire connection, said core being provided with an outstanding circumferentially extending flange near one end and in conductive connection with said core, a plurality of elongated conductors extending longitudinally of and spaced about said core, said conductors being conductively connected at one end with said flange, means surrounding the core and holding the other ends of said conductors in spaced relation therewith, and a conducting coil around said core between the latter and said conductors, said coil being free of conductive connection with all aforesaid parts and having means at its ends for connecting it in the lead-in wire of a receiving set. 120

4. An interference diverter comprising a plurality of conducting plates disposed in planes radiating from a central line, an elongated central conductor extending along said line and in conductive connection with said plates, said conductor extending away from said plates and having a ground wire connection, a plurality of 125

conducting coils spaced apart along said conductor, said coils being free of conductive connection with said conductor throughout the greater parts of their lengths but having ends in conductive connection with said conductor, and a relatively large and long conducting coil surrounding said plates and said plurality of coils, said relatively large and long coil being free of conductive connection with all aforesaid parts and having means at its ends for connecting it in the lead-in wire of a receiving set. 130

5. An interference diverter comprising a plurality of conducting plates disposed in planes radiating from a central line, an elongated central conductor extending along said line and in conductive connection with said plates, said conductor extending away from said plates and having a ground wire connection, a plurality of 135

conducting coils spaced apart along said conductor, said coils being free of conductive connection with said conductor throughout the greater parts of their lengths but having ends in conductive connection with said conductor, and a relatively large and long conducting coil surrounding said plates and said plurality of coils, said relatively large and long coil being free of conductive connection with all aforesaid parts and having means at its ends for connecting it in the lead-in wire of a receiving set. 140

5. An interference diverter comprising two spaced insulators having disk-like portions, an elongated conducting core extending between said insulators and supported by the centers of 5 said disk-like portions, said core having a ground connection, a conducting coil surrounding and out of conductive connection with said core, the ends of said coil having means for connecting the latter in the lead-in wire of a receiving set, and 10 a plurality of elongated transversely curved conducting strips extending between said insulators and secured against the peripheries of said disk-like portions of said insulators, said strips being conductively connected at one end with said core 15 and being free of conductive connection with said coil. 16. An interference diverter comprising an elongated conducting core having a ground connection, said core having an outstanding circumferentially extending flange at one end in conductive connection with said core, annular insulating means surrounding said core at the other end of the latter, elongated transversely curved conducting strips extending between and 23 secured against the peripheries of said flange and insulator, said strips being in conductive connection with said core, and a conducting coil surrounding said core between said flange and insulator and within the confines of said strips, said coil being free of conductive connection with all aforesaid parts and having means at its ends for connecting it in the lead-in wire of a receiving set. 80
7. An interference diverter comprising an insulating block having three binding posts, said block being formed of two sections recessed to jointly form an elongated cavity, said block sections being formed also with notches communicating with said cavity, an interference wave collecting and conducting core extending longitudinally in said cavity and connected with one of said binding posts, said core having supporting portions received in said notches and held by said block sections, and an incoming wave conducting coil extending longitudinally within said cavity and having its ends connected with the other two of said binding posts, said coil and core being free of conductive connection with each other. 85 90 95
